UNITED STATES PATENT OFFICE

93,175

DESIGN FOR A BUILDING

Anton Mourek, Cicero, Ill.

Application January 26, 1934, Serial No. 50,516

Term of patent 7 years

To all whom it may concern:

Be it known that I, ANTON MOUREK, a citizen of the United States, residing at 1501 South 58th Court, Cicero, county of Cook, and State of Illinois, have invented a new, original, and ornamental Design for a Building, of which the following is a specification, reference being had to the accompanying drawing, forming part thereof.

The illustration in the attached drawing shows a view, in perspective, of a building embodying my new and ornamental design.

The design may be applied to a building for various uses, such as for example, an exhibition or display building for fairs, amusement building, dancing pavilion, or a restaurant or refreshment building.

The building design may be executed in any suitable material to produce the ornamental design shown in the attached drawing.

I claim:

The ornamental design for a building as shown and described.

ANTON MOUREK.
